JACOB D. SPANG, OF DAYTON, OHIO.

Letters Patent No. 85,185, dated December 22, 1868.

IMPROVED GAS-MACHINE.

The Schedule referred to in these Letters Patent and making part of the same.

To all whom it may concern:

Be it known that I, JACOB D. SPANG, of Dayton, in the county of Montgomery, and State of Ohio, have invented a new and improved Gas-Machine; and I do hereby declare that the following is a full, clear, and exact description of the construction and operation of the same, reference being had to the annexed drawings, making a part of this specification, in which—

Figure 1 is a side elevation.

Figure 2, is a top view.

The object of this invention is to so improve the process of making illuminating-gas or vapor from naphtha, gasoline, and other hydrocarbons, that a better gas can be produced in larger quantities, and at less expense than heretofore, and the same machine can be employed, at pleasure either, for the manufacture of gas directly from the hydrocarbon, or for the carbureting of common atmospheric air, as may be desired.

In carrying this purpose into effect, I have constructed and employed, with the most complete success, an improved apparatus, which forms the subject-matter of this application, and which I will now proceed to explain in detail, making reference, for the purposes of description, to the drawings above referred to, in which—

A represents the vessel, in which is contained the gasoline or other hydrocarbon, from which the gas is to be made, *a* being a funnel, provided with a stop-cock, through which the material is introduced into the vessel, and

B being a pipe, provided with a stop-cock, *b*, through which so much of such material as is required for the purpose of making gas at any time is fed from the vessel to the apparatus, which vaporizes it and fixes the gas.

After passing from the vessel A, the pipe B is coiled back and forth a great many times upon a low, flat frame, C, over a shallow vessel, D, so that a great extent of the pipe will be subjected to the influence of hot air rising from the vessel D.

The pipe then extends to a gasometer, E, with which it communicates, after which it extends back to the centre of the vessel D, directly under the coils and involutions formed by itself above the vessel, and is there provided with one or more suitable burners, F.

Stop-cocks *b*¹ *b*² are provided on each side of its connection with the gasometer, in order to regulate and control the action of the gas.

The gasometer is of the form which is commonly to be seen in large establishments for the manufacture of illuminating-gas, having a water-sealed gas-cylinder, *e*, rising and falling in a water-cylinder, *e'*, by the pressure of the gas, and guided and supported by a frame, G.

It is also provided with a cord, *h*, pulleys *h'* *h''*, and a crank, H, by which the gas-cylinder can be raised or lowered at pleasure, and with a stop-cock, *i*, by which gas or air can be allowed to escape, or water can be supplied, as circumstances may require.

I is a pipe, by which the gas is taken from the reservoir E to be used.

Immediately after passing from the gasometer, it branches off to right and left, one branch, J, terminating near by in a burner, K, by which the quality of the gas may at any time be tested before it can enter the pipes where it is to be used.

When thus testing the gas, the stop-cock *j* of the other branch is to be closed.

When not testing the gas, the stop-cock *j'* of the branch J is to be closed, and the stop-cock *j* opened.

The gas then flows along through pipe I into a horizontal semi-cylindrical vessel, L, where it may be subjected to a bath, for the purpose of purifying it, or to the action of any substances, for the purpose of enriching it, or otherwise varying its quality.

After leaving the vessel L, it passes through another similar vessel, M.

It is then conducted to the second gasometer or reservoir N, from which a pipe, O, carries it to the burners *o*, where it is to be consumed.

By employing the two vessels L and M, the quality of the gas can be changed and controlled to any required degree, one of them being used to purify it, and the other to vary its quality, by enriching it, or both may be used for purifying it, if desired.

Each vessel is provided with a cock or funnel, *l m*, by which the substances employed in it may be readily introduced or removed.

After leaving the vessel M, the pipe I connects with a side-pipe, P, leading from an air-pump, Q, by means of which the gas can be diluted to any required extent before passing into the reservoir whence it is to be taken for use.

Suitable stop-cocks *p* *q* are employed, at this point, on each side of the connection.

It will be observed that the pipe I enters the vessel L at its top, and emerges at its bottom, and enters the vessel M at its bottom, emerging at its top, and, also, that, between the vessels, and at either extremity of them, it bends upward and over, in the form of an arch. This construction is adopted in order to properly conduct the gas or vapor through the fluids in the vessels, without allowing any communication of the fluids from one vessel to another.

The operation of the combined apparatus, which I have herein described, is exceedingly perfect and effective, manufacturing a very superior quality of gas, at a less expense than by any other machine, and enabling the operator, in fact, to produce gas of any quality desired.

In the practical operation of the apparatus, the gasoline or other hydrocarbon is introduced into the tank A, and a little fire is made or placed in the vessel D, sufficient to heat the coiled pipe B over it. The cock *b* is then opened, or partially opened, and the gasoline permitted to flow from the tank. In passing through the involutions of the pipe, over the heated vessel, it

is rapidly vaporized, and, in the form of gas, enters the gasometer E. As soon as the latter has been partially filled, the fire may be removed from the vessel D, or allowed to go out, and the burner F may be lighted, from which sufficient heat will be continuously supplied, to keep up the process as long as desired.

After the gasometer E has been thus supplied, the quality of the gas may be tested by the burner K, and, if found to be poor, it may be improved by means of the vessel L or M, while, if too rich, as will usually be the case, it may be diluted with air from the pump Q. It can thus be adjusted and controlled perfectly.

By means of the air-pump Q and the vessels M and L, the process may be partially reversed, if desired, and the gasometer E filled through the pipe I. In this case, the vessels M and L are to be partially filled with gasoline, the cocks p and j closed, and the air is to be forced from the air-pump, through the gasoline, to the gasometer. The latter having been filled, the gas or carburetted air can be heated and fixed by means of the coiled pipe B and the lighted burner beneath it,

and then conducted away to a suitable reservoir, for use; or, after filling the gasometer, the cock p may be opened, and the carburetted air allowed to pass back through the vessels L and M to the gasometer N, as described above. In this manner, the air will be doubly carburetted, once in passing to the reservoir E, and once in passing back to the reservoir N. On its return passage, if found to be too rich, it can be diluted by the pump Q, as before described.

Having thus described my invention,

What I claim as new, and desire to secure by Letters Patent, is—

The arrangement of the tank A, coiled or involuted pipe B, gasometer E, burner F, vessel D, pipe I, vessels L and M, air-pump Q, and gasometer N, when the said parts are provided with suitable cocks, and constructed to operate in the manner and for the purpose indicated.
